HUGO SCHMIDT, OF CHARLOTTENBURG, GERMANY, ASSIGNOR TO THE FIRM OF "ESTO" ELASTISCHER STRASSENBahn-OBERBAU G. M. B. H., OF BERLIN-WILMERSDORF, GERMANY.

PERMANENT WAY FOR TRAMWAYS IN ASPHALT PAVING AND THE LIKE.

1,149,167.

Specification of Letters Patent.

Patented Aug. 3, 1915.

Application filed March 6, 1914. Serial No. 822,991.

To all whom it may concern:

Be it known that I, HUGO SCHMIDT, a subject of the Emperor of Germany, residing at Bismarckstrasse 66, Charlottenburg, near Berlin, Germany, have invented certain new and useful Improvements in Permanent Ways for Tramways in Asphalt Paving and the like; and I do hereby declare the following to be a full, clear, and exact description 10 of the invention, such as will enable others skilled in the art to which it appertains to make and use the same, reference being had to the accompanying drawings, and to letters or figures of reference marked thereon, 15 which form a part of this specification.

A problem in the construction of the permanent way for tramways which has hitherto not been solved, was to lay the tramway rails in such a manner in asphalt paving, 20 that the asphalt would not be as quickly as hitherto destroyed alongside of the rails. In the mostly employed rigid systems of the permanent way it has been attempted to secure such durability of the pavement by 25 employing heavy rails with as great a bending strength as possible, and by connecting these rails in as rigid a manner as possible with the concrete bedding by means of reinforced concrete plates, anchoring bolts and 30 the like.

The early wear and destruction of the pavement alongside of the rails is a result of the fact that the vibrations and blows, which the wheels of the cars produce in the 35 direction of their travel on the rigidly laid rails will, on the one hand, slacken the cohesion between the asphalt and the sides of the rail, and, on the other hand, result in excessive strains on the surface of the rails, 40 which lead to corrugations or waves, and eventually destroy the concrete bedding under the rails, which cannot forever withstand these attacks. As soon as there is the least slack between rail and asphalt, the 45 water entering into the crevices will very quickly complete the destruction.

In recent years it has been tried to avoid the disadvantages caused by the rigidity of the tracks by elastically supporting the rail 50 on wooden sleepers, which were embedded in the foundation layer of concrete of the road-

way. This method, indeed, afforded the advantages inherent in the elastic bedding, namely economization of the rails and rolling stock and reduction of the noise. But 55 the movements of the elastically supported rail under the load rolling over it would far more quickly result in a loosening of the rail from the asphalt and concrete adhering to it, and in a destruction of the latter. This 60 method thus proved a failure as regards the object of improving the durability of the road pavement. The problem of utilizing the advantage of an elastic supporting of the rail in favor of the latter and the rolling 65 stock without any injurious effects on the pavement of the road can be considered as solved only, if it is rendered possible to keep the hard shocks away from those parts of the structure of the permanent way, to which 70 the asphalt paving and the concrete are joined. This object is obtained by the present invention.

In the accompanying drawings Figures 1, 2 and 3 are cross sections through three 75 varieties of the invention which are explained in the following specification.

The permanent way, constructed according to the present, novel method is shown in cross section in Fig. 1. It meets the requirements in the following manner. It is composed of essentially two parts, the rail *a* and the rail box *d*, separating the said rail *a* from the asphalt *b* and the concrete foundation *c*. Contrary to other known arrangements, rail and rail box are, however, not rigidly connected directly to each other by means of metallic parts. The essential feature of the present invention consists in that the rail is on all sides completely insulated 85 from the rail box by elastic intermediate parts.

In Figs. 1 to 3 several constructional forms of the invention are exemplified, by which the rail is elastically insulated from 90 the rail box.

In the constructional form shown in Fig. 1 the rail is separated below from the rail box by means of an elastic layer, a wooden sleeper *e*, and at the two sides by intervening spaces, which are filled with an elastic medium (impregnated soft wood *f*, rubber 100

or the like). The arrangement of this medium must be such, that it will not suffer by the vibrations of the adjoining rail nor by water, as little as the longitudinal sleeper on which the rail is laid.

In the constructional form according to Fig. 2 the rail box is protected from the blows of the car wheels against the top of the rail by the rail being in itself elastic, and thus not requiring an elastic bedding. As the broad bottom of the rail is supported at the edges only on the bottom of the box and thus secured, the top of the rail can elastically yield, both in a vertical and in a lateral direction.

In the constructional form shown in Fig. 3, in particular for wood pavements, the elastic insulation is obtained, the same as in Fig. 1, by means of a wooden bedding. Only here this wooden bedding need not be insulated from the wood pavement as it was necessary with the concrete pavement.

With all three constructional forms shown the vibrations are, thus, actually insulated from the asphalt paving and the parts contacting therewith, or, at least, weakened to such an extent, that no gap will be produced between these parts and the asphalt covering and the concrete, as the rail can unrestrictedly yield elastically, without the rail box forming the separation from the road pavement and this road pavement itself being affected thereby. A further feature is that the pressure on the concrete foundation is, by the interposition of the broad box, reduced to the half of the pressure which would occur if the rail were rigidly embedded in the concrete.

In order to insure a permanent contact between the road covering (asphalt) and the rail box, the latter is provided with flanges which engage under the said road covering, and are embedded in the body of the pavement, and preferably anchored therein. These flanges are, furthermore, used for obtaining joints, which are proof against bending strains, between the individual boxes.

In the constructional form according to Fig. 1 the rail *a* is clamped, say, every 50 meter, to the wooden sleeper *e* resting on the bottom of the box, by means of elastic clamping parts *h*. These will, by their shape, be adapted to the shape of the bottom of the rail, and by their bearing against the walls of the boxes, prevent any displacement of the rail from the axial line under action of lateral forces. These clamping parts consist of short pieces of hardwood *h*, having a wedge-shaped section, and which 55 press the bottom of the rail tightly against the bedding by means of screw bolts *l*, passing through slotted holes in the bottom of the box. For uniformly distributing the pressure of this screw on the hardwood 60 block iron angle-shaped plates *w* are pro-

vided between the nut and the wooden block. The elastic clamping part may, as shown in Fig. 2, also be made entirely of iron (*n*, *n'*). The clamp *n'* is secured by means of the screw *r*. It may, however, if 70 it is made to bear against a lug *m* of the wall of the box, also allow of clamping the bottom of the rail in a sufficient manner to the bottom of the box without the need of any screws (see the left side of Fig. 2.) 75

In the constructional form according to Fig. 2 the elastic bottom of the rail is supported at the sides by small lugs only, so that the rail can vibrate in a vertical direction. 80

In the constructional form according to Fig. 3 for wood pavements the two sides of the box *d* are securely held together by means of a screw *s*. The wooden bed sleeper is secured by the screw bolt *r*, and 85 the rail by the coach screws *t*. The space at the sides of the top of the rail is filled with wooden paving blocks *f* jointed with asphalt. 90

The reinforcing flanges *o* of the box walls (Figs. 1 and 2) are not in the level of the road, but about at the point where the road covering, namely the asphalt or the wood paving commences. The car wheel which may be resting on the asphalt, which in summer is very elastic, will therefore not buckle the wall of the box, but, on the contrary, by its weight hold the flange, and with the same also the wall, in position, and prevent a crevice or crack being formed 100 along the edge of the box. These flanges may be either rigidly connected with the boxes, or may consist of angles secured thereto by means of screws. For facilitating their being underpacked, they are made 105 of a flat shape and are drilled at a certain pitch. Through these holes anchors *p* are engaged for further securing the walls in a lateral direction. These flanges are at the same time also used, in combination with 110 the extended bottoms of their bedding to produce a cheap, reliable joint, proof against bending stresses, between each two boxes. 115

In the permanent way constructed according to the present invention the elastic bedding of the rail affords a very considerable economization of the cars and of the rail, as well, and great saving in the cost for their maintenance, and a reduction of the noise. All parts of the permanent way 120 which are contained in the rail box, such as the rail itself, the means for fixing it and its bedding, and the wood packing at the sides can be readily renewed with little cost. 125

I claim:

1. Permanent way for tramways in asphalt paving and the like, in which the rail is elastically bedded in a rail box, and the space between the rail and the walls of the 130

said box is filled with an elastic medium, the said rail held to its bed by elastic clamping means.

2. Permanent way for tramways in asphalt paving and the like, in which the rail is elastically bedded in a rail box, and the space between the rail and the walls of the said box is filled with an elastic medium, the said rail held to its bed by a wedge 10 made of an elastic material and bearing against the walls of said box, and driven by suitable means.

3. Permanent way for tramways in asphalt paving and the like, in which the rail 15 is elastically bedded in a rail box, and the space between the rail and the walls of the said box is filled with an elastic medium, the said rail held to its bed by elastic iron clamps.

20 4. Permanent way for tramways in asphalt paving and the like, in which the rail is elastically bedded in a rail box, and the space between the rail and the walls of the said box is filled with an elastic medium, 25 the said rail held to its bed by elastic means,

the said rail box having on its outsides flanges engaging in the body of the roadbed beneath the road covering and anchored to said roadbed.

5. Permanent way for tramways in asphalt paving and the like, in which the rail is elastically bedded in a rail box, and the space between the rail and the walls of the said box is filled with an elastic medium, 30 the said rail held to its bed by elastic means, 35 the said rail box having on its outsides flanges engaging in the body of the roadbed beneath the road covering and anchored to said roadbed, the said rail boxes jointed to each other by aid of said flanges and the 40 extended bases in a manner proof against bending stresses.

In testimony that I claim the foregoing as my invention, I have signed my name in presence of two subscribing witnesses.

HUGO SCHMIDT.
